UNITED STATES PATENT OFFICE.

ALEXANDRE WILLK, OF PARIS, FRANCE.

FOLDING POWDER PUFF.

Application filed March 17, 1926, Serial No. 95,360, and in France August 25, 1925.

My present invention relates to a powder puff adapted for the use of face powder or like products; and I thus obtain a folding or disappearing powder puff which occupies a very small space and may be readily transported, for instance in a lady's hand bag together with the usual color sticks, sprayers or the like, serving for toilet purposes. In my said device I combine the powder puff 10 and the powder box which is used with the same, the face powder being placed within the device supporting the powder puff.

The following description and appended drawings show by way of example various 15 embodiments of the said invention.

Fig. 1 is a vertical section of the powder puff according to the invention, in the extended position.

Fig. 2 is a horizontal section in the line 20 A—B of Fig. 1.

Fig. 3 is a vertical section of the powder puff in the folded position.

Figs. 4 and 5 are respective elevational views of the said powder puff inclosed in 25 its casing and in the operative position.

Figs. 6 and 7 show modifications of my said device.

In the figures, 1 is the support or holder for the powder puff which has the form of a 30 hollow cylinder, whereof the upper end 2 carries a central sleeve 3 integral therewith, and the lower end consists of a cylindrical box 4 inserted into the cylinder 1 and comprising an external flange 5. Upon the cylinder 1 is slidable a sleeve 6 having in the 35 interior the slots 7 in which are engaged the studs 8 mounted upon the external part of the end 2 of the cylinder 1. The reciprocating motion of the sleeve 6 is limited at one 40 side by the edge 5 of the box 4 and at the other side by the tappets 9 mounted on the interior of the sleeve 6 at its lower part which co-operate with studs 8 mounted on the cylinder 1.

To the upper part of the end 2 of the cylinder 1 is secured a toothed circular member 45 provided with a central aperture corresponding to the sleeve 3; between the teeth are disposed the springs 11 which are wound 50 at one end upon a suitable support 12 and are secured at the other end to the edge of the powder puff 13. The said powder puff is secured to the support 11 by suitable means, and a socket 14 inserted within the 55 said sleeve 3 maintains the powder puff in

the central position, while affording a free connection with the interior of the cylinder 1.

The operation is as follows:

The sleeve 6 being applied against the flange 5 of the box 4, the springs 11 are entirely disengaged and the powder puff 13 is fully opened, thus occupying the position shown in Figs. 1 and 5.

But if, as shown in Fig. 3, the sleeve 6 is raised, while holding the cylinder 1 and sliding the slots 7 upon the studs 8, the top part of the said sleeve will press against the central part of the springs 11, so that according to the motion of the sleeve the springs 11 will be bent, and the powder puff 13 will be brought within the sleeve 6. When the said sleeve is at the end of its upward stroke, i. e. when the tappets 9 make contact with the studs 8, the powder puff will be completely stowed within the sleeve 6, which may now, be provided with a cover 15, as shown in Fig. 4.

The box 4 and the cylinder 1 may contain the powder falling from the puff 13 through the sleeve 3 and the socket 14, when the said puff is extended for use.

This will afford a powder puff device which occupies a limited space and can be readily handled. The arrangement herein represented is shown solely by way of example, and I may vary the means for securing the powder puff to the cylinder 1, and also the method of sliding the sleeve 6 on the cylinder 1, and the form of the springs 10; I may provide upon the cylinder 1 a flange 5 which is distinct from the flange of the powder box 4, without departing from the principle of the invention.

In the device shown in Figs. 6 and 7, the support for the powder puff is the same as the one shown in Figs. 1 to 5. The powder puff 13 is mounted at the top of a small cylindrical case 1 in which the powder is placed. The bottom of said case consists of a cover 100 4' whereby the powder can be renewed.

The said small cylindrical case is slidable by easy friction within a cylinder 17 which is slotted at the top and comprises a helical groove 18. The said cylinder is rotated, but 105 without removal, in an external cylinder 16 which latter and the cylinder 17 are united at the bottom by means affording the rotation of the member 17 relatively to the member 16.

The recipient 1 is vertically guided, and it comprises a stud engaging in a slot 18, so that when the cylinder 17 is turned relatively to the element 16 in either direction, 5 the recipient holding the powder puff can be raised or lowered. The tube 16 is provided with a suitable cover, not shown.

Claims—

1. A folding powder puff comprising in combination, a puff provided with spring members for sustaining the puff in its open position, a powder container, means for securing said spring members to said container, and a sleeve slidably on said container for contracting the spring members

to fold said puff, said sleeve being adapted to enclose said puff in its folded position.

2. A folding powder puff as claimed in claim 1, said container being provided with a centrally disposed tubular member, said 20 tubular member being open at each end, one end of said tubular member terminating adjacent the securing means for said springs, the other end terminating within the powder container, whereby powder is conveyed from 25 said container to said puff.

In testimony whereof I affix my signature.

ALEXANDRE WILLK.
